UNITED STATES PATENT OFFICE

141,684

DESIGN FOR A COMBINATION LIGHTER AND CIGARETTE CASE

William D. Gladstone, New York, N. Y.

Application March 28, 1945, Serial No. 118,744

Term of patent 14 years

(Cl. D48—24)

To all whom it may concern:

Be it known that I, William D. Gladstone, a citizen of the United States, residing at 1307 Sixth Avenue, New York, in the county of New York and State of New York, have invented a new, original, and ornamental Design for a Combination Lighter and Cigarette Case, of which the following is a specification, reference being had to the accompanying drawing, forming part thereof.

Fig. 1 is a side elevational view of a combination lighter and cigarette case, showing my new design;

Fig. 2 is an elevational view as seen from the left of Fig. 1;

Fig. 3 is also an elevational view as seen from the right of Fig. 1; and

Fig. 4 is a top plan view of Fig. 1.

I claim:

The ornamental design for a combination lighter and cigarette case, as shown.

WILLIAM D. GLADSTONE.
